US00D531320S

(12) **United States Design Patent** (10) **Patent No.:** **US D531,320 S**
(45) **Date of Patent:** **** Oct. 31, 2006**

(54) **CASSETTE FOR ORGAN TRANSPORTER**

(75) Inventors: **Jeffrey C. Garland**, Littleton, CO (US); **Douglas A. Schein**, Des Plaines, IL (US)

(73) Assignee: **Organ Recovery Systems**, Des Plaines, IL (US)

(**) Term: **14 Years**

(21) Appl. No.: **29/179,035**

(22) Filed: **Apr. 4, 2003**

(51) **LOC (8) Cl.** **24-02**

(52) **U.S. Cl.** **D24/216; D24/107**

(58) **Field of Classification Search** D24/111, D24/216, 108, 133, 107, 121, 128; 435/1.2, 435/284.1, 307.1, 303.1; 62/306, 78, 371; 128/DIG. 26; 604/19

See application file for complete search history.

(57) **CLAIM**

The ornamental design for a cassette for organ transporter, as shown and described.

DESCRIPTION

FIG. 1 is a perspective view of a cassette for organ transporter made of an opaque material;

FIG. 2 is a top view thereof;

FIG. 3 is a bottom view thereof;

FIG. 4 is a front view thereof;

FIG. 5 is a rear view thereof; and

FIG. 6 is a side view thereof, the opposite side view being a mirror image;

FIG. 7 is a perspective view of the cassette for organ transporter made of a transparent material;

FIG. 8 is a top view thereof;

FIG. 9 is a bottom view thereof;

FIG. 10 is a front view thereof;

FIG. 11 is a rear view thereof; and,

FIG. 12 is a side view thereof, the opposite side view being a mirror image.

1 Claim, 12 Drawing Sheets
